UNITED STATES PATENT OFFICE.

ALBERT R. WALKER, OF ST. LOUIS, MISSOURI, ASSIGNOR TO WINDHORST & COMPANY, OF ST. LOUIS, MISSOURI, A FIRM.

GAS-LIGHTING APPARATUS.

1,032,791.

Specification of Letters Patent. Patented July 16, 1912.

Application filed August 22, 1910. Serial No. 578,385.

To all whom it may concern:

Be it known that I, ALBERT R. WALKER, a citizen of the United States, and a resident of the city of St. Louis and State of Missouri, have invented a new and useful Improvement in Gas-Lighting Apparatus, of which the following is a specification.

This invention relates to gas lighting apparatus and more particularly to gasoline gas pressure systems.

It has for its principal objects to secure a maximum candle power with an expenditure of a minimum of gas, and to secure certain advantages hereinafter more fully appearing.

The invention consists in the parts and in the arrangements and combinations of parts hereinafter described and claimed.

In the accompanying drawing which forms part of this specification and wherein like symbols refer to like parts whereever they occur, Figure 1 is a view partly in elevation and partly in vertical section illustrating a portable hot process gasoline gas apparatus embodying my invention; Fig. 2 is a section on the line 2—2 of Fig. 1; Fig. 3 is a fragmentary elevation of a modified construction and arrangement of lighting arms; and Fig. 4 is a similar view showing a further modification of the lighting arms.

As illustrated in the drawings, the apparatus comprises what is known as a "hot process" gasoline gas generator which is mounted in a suitable casing or housing 1. In the lower portion of the housing is a tank 2 which contains gasoline under pressure. Leading from the tank 2 is a pipe or tube 3 of small diameter. This pipe 3 is connected to the lower end of a vertical tube 4 which is mounted in a box or frame 5 in the upper portion of the housing 1. Communication between the pipe 3 and tube 4 is controlled by a suitable valve 6 so that the flow of liquid into the pipe 4 may be regulated. Communicating with the upper portion of the pipe 4 is a horizontal tube or pipe 7 whose outer end extends through the casing 1 and is open to the outside atmosphere. The outer end of this pipe 7 is preferably covered with wire gauze 8. A by-pass or return pipe 9 is connected at one end to the pipe 4 above the air pipe 7 and at its opposite end to a gas burner 10 which surrounds the pipe 4 below said air pipe 7; and mounted on the pipe 4 above the

burner 10 is a baffle plate or deflector 11. Surrounding the pipe 4 below the burner 10 is a cup or receptacle 12.

The arrangement of the parts above described constitutes an ordinary hot process gasoline gas generator. In its operation, the tank 2 is supplied with a quantity of gasoline. The tank is then pumped up with air pressure and the valve 6 is opened to admit the gasoline into the pipe 4 through the pipe 3. A quantity of gasoline, alcohol or other suitable oil is poured into the receptacle 12 and ignited. The flame from the burning oil in the receptacle 12 heats the pipe 4 and vaporizes the gasoline which enters the same, and the vapor mixes with air which is drawn in through the tube 7, said mixture of vapor and air passing into a tubular upright or post 13 which is mounted on the casing 1 and is connected at its lower end with said pipe 4. A portion of the gas thus generated is conducted through the return pipe 9 to the fuel burner 10 which is ignited and keeps the tube 4 continually heated after the oil is burned out of the receptacle 12.

Extending laterally from the upper end portion of the tubular upright or pipe 13 are a pair of horizontal pipes or tubular arms 14, 15. Depending from each of these pipes are a series of nozzles 16 on the lower ends of which are secured inverted incandescent gas-light mantles 17. Mounted on the upper horizontal tubular arm or pipe 14 is an angular reflector 18. This reflector is preferably secured to said horizontal pipe 14 by brackets 19 having sleeve portions 20 which are loosely fitted over the pipe and secured in place by set screws 21. On the lower horizontal pipe 15 is a similarly mounted concave or semicylindrical reflector 22. By pivoting the reflectors on the pipes 14 and 15 as shown, said reflectors may be tilted to different angles so as to reflect and concentrate the light to a restricted area for photographic purposes or other cases where it is desirable to have strong light. By the arrangement of a horizontal row or battery of inverted lights substantially as shown, advantageous results are obtained which have heretofore been accomplished only through the medium of an arrangement of lights which is more complicated and consumes a greater amount of gas. In fact, satisfactory results in photographing by

artificial light have generally been successfully accomplished by the use of a horizontally disposed electric tube.

Instead of having a pair of arms projecting to one side of the pipe 13, a single cross arm 14^a may be provided as shown in Fig. 3, or, as shown in Fig. 4, a pair of cross arms 14^b and 15^b may be provided. So, too, in some cases, a greater number of the horizontal arms may be provided.

Obviously, the apparatus admits of considerable modification without departing from my invention. Therefore, I do not wish to be limited to the specific construction and arrangement shown.

What I claim is:

1. A portable gas lighting stand comprising a base, a standard thereon, a horizontal arm on said standard, a series of closely associated burner elements depending from said arm, inverted gas mantles on said burner elements, and a reflector pivoted on said arm in coöperative relation to all of said burner elements.
2. A portable gas lighting stand comprising a base, a standard thereon, a multiplicity of horizontal arms on said standard, a series

of closely associated inverted incandescent gas burners on each of said arms, and separate elongated reflectors pivoted on the respective arms in coöperative relation to the series of burners thereon.

3. In a gas lighting apparatus, a portable stand comprising a base, a standard thereon, a pair of horizontal pipes mounted on said standard in vertical alinement, each of said pipes having a multiplicity of closely associated pendent incandescent gas burners thereon, a reflector pivotally mounted on the uppermost pipe and extending throughout the length of the series of burners thereon, said reflector having a portion overhanging said pipe and a portion depending at one side thereof, and a concaved reflector pivoted near its upper edge to the lower pipe and extending throughout the length of the series of burners thereon.

Signed at St. Louis, Missouri, this 17th day of August, 1910.

ALBERT R. WALKER.
